UNITED STATES PATENT OFFICE.

GEORGE W. BANKS, OF PHILADELPHIA, PENNSYLVANIA.

GRIPPER FOR JOB-PRESSES.

SPECIFICATION forming part of Letters Patent No. 439,462, dated October 28, 1890.

Application filed April 10, 1890. Serial No. 347,340. (No model.)

To all whom it may concern:

Be it known that I, GEORGE W. BANKS, of Philadelphia, in the county of Philadelphia and State of Pennsylvania, have invented a new and useful Improvement in Grippers for Job-Presses, of which the following is a full, clear, and exact description.

My invention relates to an improvement in grippers especially adapted for attachment to job-presses, and has for its object to provide a means whereby the grippers may be set without the aid of a wrench or similar tool, and also whereby when set they will be retained in a positively-fixed position upon the gripper-plate and rendered incapable of lateral movement until purposely adjusted.

The invention consists in the novel construction and combination of the several parts, as will be hereinafter fully set forth, and pointed out in the claims.

Reference is to be had to the accompanying drawings, forming a part of this specification, in which similar figures of reference indicate corresponding parts in all the views.

Figure 1 is a front elevation of the device applied to the platen of a job-press. Fig. 2 is a side edge view of the device detached. Fig. 3 is a transverse section on line 3 3 of Fig. 2, and Fig. 4 is a perspective view of one of the gripper-arms, the view being taken from the under side thereof.

In carrying out the invention the gripper-plate 10 is provided with preferably two longitudinal slots or openings 11, one at each side of its center, and in the upper face of the said plate a series of transverse teeth or deep serrations 12 is produced. The gripper-arms 13, which may be either straight, curved, or angular, have longitudinal teeth or serrations 14 formed in their under sides at one end, as best shown in Fig. 4, and an opening or aperture 15 at said toothed end extending through from the front to the rear.

In connection with each gripper-arm a bolt 16 is employed, the threaded ends of the said bolts being projected upward through the slots 11 of the plate and through the apertures in the arms, the toothed surfaces of said arms having previously been brought in contact with the toothed surfaces of the gripper-plate. The heads of the bolts contact with the under face of the gripper-plate, and upon the upwardly-extending threaded end of each bolt a winged nut 17 is screwed to a bearing 18 upon the arm immediately below it. It is

evident that when the toothed surfaces of the gripper-plate and arms are brought into engagement and the winged nuts screwed down upon the arms it will be impossible for said arms to move laterally to the slightest extent, and that by turning back the winged nuts either gripper-arm may be readily adjusted sidewise upon the plate. It is also evident that the nuts and arms may be manipulated by the hands of the operator without the assistance of a wrench or of a tool of like character, which has heretofore been required, and, as the space in job-presses in which the wrench must be turned to adjust the gripper-arms is very limited, when such a tool is employed the hands of the operator are often injured. The possibility of such results is removed by the improved construction set forth.

The gripper-plate may be attached to the platen 18 and tripped in any approved manner. I have shown one form of attachment in the drawings, consisting of journaling trunnions 19, located at the ends of the plate, in sockets 20, secured to the sides of the platen, the plate being provided, also, near one end with an arm 21, to be acted upon by the tripping mechanism of the press.

Having thus described my invention, I claim as new and desire to secure by Letters Patent—

1. The combination, with the platen 18, having two sockets or bearings 20, of the transverse plate 10, having end trunnions 19, mounted in said sockets and provided with longitudinal slots 11, the grippers 13, having apertured lower ends, bolts 16, passed upward through slots 11 and the apertures in the grippers and provided with thumb-nuts 17, and the operating-arm 21, projecting from the bar 10, substantially as set forth.

2. A gripper-bar having a corrugated or toothed upper face 12, provided with longitudinal slots 11, trunnions 19 at the ends of the plate, the operating-arm 21, the grippers 13, having apertures 15 and longitudinal serrations 14 at the under side of their inner ends, registering, respectively, with the slots and serrations 11 12, and bolts 16, passed up through the slots and apertures and provided with thumb-nuts 17, substantially as set forth.

GEORGE W. BANKS.
